CLAIM

The ornamental design for a range and/or components thereof, as shown and described.

DESCRIPTION

FIG. 1 is a front perspective view of a foot for a range according to our new ornamental design;

FIG. 2 is a front view thereof, with the left, right and rear sides being identical;

FIG. 3 is a top view thereof; and,

FIG. 4 is a bottom view thereof.

The broken lines represent environment or structure of the kitchen appliance and do not form any part of the claimed design.

The dotted lines (e.g., in FIGS. 1, 3 and 6) represent the border between claimed and unclaimed subject matter and form no part of the claimed design.

Throughout the drawings, various views may not be provided, as the components in these views are unornamented or the ornamentation in these views is simply unclaimed.
